N. C. DE LOSS

LOOSE LEAF BINDER

Filed June 23, 1927

FIG. 3.

FIG. 2.

By Norman Claybaugh De Loss
Inventor

Franklin-Spong Company

UNITED STATES PATENT OFFICE.

NORMAN CLAYBAUGH DE LOSS, OF SHAKER HEIGHTS, OHIO.

LOOSE-LEAF BINDER.

Application filed June 23, 1927. Serial No. 200,788.

My invention relates to loose leaf binders and more particularly it relates to an improved binder-locking mechanism therefor.

An object of my invention resides in the provision of an improved binder-locking mechanism for clamping a plurality of binder leaves together in a systematic manner and to facilitate handling of the same.

Another object of my invention is to provide an improved binder-locking mechanism which may be expeditiously actuated by a simple movement to quickly release the locking mechanism to enable leaves to be inserted into the binder or to be withdrawn therefrom.

Another object of my invention resides in the provision of an improved locking mechanism for loose leaf binders which is durable in construction, positive in operation, and which may be economically produced by virtue of the minimum number of inexpensive parts comprising the same.

These and other objects of my invention and the invention itself will become apparent from reference to the following description of an embodiment thereof and in which description reference will be had to the annexed drawings forming a part of this specification.

Referring to the drawings:

Fig. 1 is a plan view of an embodiment of my invention, some of the parts comprising the same being shown in section;

Fig. 2 is a transverse sectional view taken on the line 2—2 of Fig. 1; and

Fig. 3 is a sectional view of the foregoing embodiment taken on the line 3—3 of Fig. 2.

Referring to all the figures of the drawings, in all of which like parts are designated by like reference characters, and wherein I have illustrated an embodiment of my invention, preferably comprising a housing or casing 10 formed of a lightweight metallic material such as aluminum or the like and having heavy fabric 11, such as buckram or the like riveted to a side wall at 8 and extending about a binder-cover body 12 formed of cardboard or the like material. The fabric may be riveted together at 7 to strengthen the same and provides a hinge connection at 17 between the casing and binder cover. A padding 6 or the like may be disposed on the outside of the covers.

At 13, I show a lower binder section

formed of cardboard or the like material and having metallic reenforcing plates 14 thereon adapted to support a pair of binder posts 15 and 16 extending upwardly therefrom and projected towards the metallic casing or housing 10. The plate 14 is also covered with a heavy fabric 5 which also provides a hinge connection between this plate and a second binder cover, not shown, but substantially the same as the cover 12.

The top and bottom walls 19 and 20 of the casing 10 are provided with a pair of aligned apertures adjacent the ends thereof through which the posts 15 and 16 may be projected and disposed with a portion within the housing 10. The top wall 19 is preferably removable by withdrawing screws 4 to permit access to the interior of the casing 10 and to facilitate assembly of the locking mechanism for the binder which will hereinafter be described in detail. A pair of bearing brackets 21 and 22 are disposed in the casing 10 depending from the inner side of the removable top wall thereof and providing supporting bearings upon which a horizontally disposed rod 24 is journaled within the casing with its ends disposed adjacent to the binder posts. Axially extending hollow threaded bores 25 and 26 are formed in ends of outer sections 65 and 66 of the rod 24 into which bores are screw-threaded the short threaded end portions 27 and 28 of a pair of gripping jaw members 29 and 30. These jaw members are formed with looped portions 31 and 32 through which the posts 15 and 16 extend when projecting into the apertures 2 and 3 of the top and bottom walls of the casing.

The threaded connection between the rod and jaw members are right and left-hand threads, respectively, and thus rotation of the rod in its bearings in one direction will cause the jaw members to be moved relatively towards each other or away from each other depending upon the direction of rotation of the rod, in a manner similar to a turnbuckle, both as to the construction and operation thereof. The threaded connection being capable of giving but a relatively short movement of the jaw members axially in either and opposite directions, it is only necessary that the rod 24 be rotated a few turns to effect the desired movement of the jaw members to engage or disengage them with the binder posts 15 and 16. The rod 24

is preferably formed of a plurality of joined sections. A rotatable knob or operating handle 36 is slidably mounted on the intermediate non-circular portion 63 of the rod 5 and is provided with a non-circular bore 37 into which the intermediate portion 63 is disposed and thus the rod and knob are non-rotatable relative to each other, but, at the same time, permit the knob to be slid 10 axially on the rod for a purpose which will hereinafter be set forth. The periphery of the knob is roughened or knurled to facilitate the rotating of the same by the finger or thumb of a user of the binder, lessening 15 the possibility of slippage. The ends of the portion 63 of the rod are recessed and are adapted to receive a reduced end 64 of the outer rod sections 65 and 66, the three sections being joined together by virtue of 20 transverse pins 67.

An opening 39 is provided in the top wall of the casing intermediate the ends thereof through which the knob periphery extends and projects above the top wall outer surface 25 and thus a user may rotate the knob by engaging a finger with the knurled periphery thereof and thereby move the jaw members relative to each other. Small recesses 40 are formed in the side 41 of the knob and arranged in a circular formation around the center thereof, and are adapted to receive a pin 42 carried by the top wall of the casing and projecting into the opening 39. When the knob is slid to the left, the pin 30 telescopes into one of the recesses 40 and thus locks the knob against accidental movement.

When for any reason it is desired to insert or remove binder leaves from the binder, 40 a user of the afore-described binder may by a simple operation shift the knob to the right by a finger or thumb engaging with the same, and then by rotating the same in the direction of the arrow 50, Fig. 1, cause 45 the jaw members to be moved towards each other, disengaging the jaw members from contact with the posts 15 and 16, and thus the binder cover 12 may be withdrawn from the posts 15 and 16, enabling binder leaves 50 to be inserted therein or permitting withdrawal of the binder leaves therefrom. By virtue of the limited number of threads on the jaw members at 27 and 28, movement of the jaw members towards each other is 55 but a limited one, and thus it is not possible for them to engage the posts 15 and 16 by rotating the rod 24 in the direction of the arrow 50.

In order to cause the jaw members to 60 grip the binder posts after leaves have been inserted in the binder and the casing has been placed over the binder posts and to prevent accidental relative movement of the cover, the knob may be rotated in the direction opposite to that of the arrow 51 which

rotates the rod 24 moving the jaw members away from each other by virtue of the threaded connection therebetween, and thus the portion 60 and 61 of the ring portions of the jaw members are contacted with the 70 posts and lock the binder covers onto the posts 15 and 16.

The hinge connection between the binder covers and the casing 10 and stationary section 13 will enable the binder covers to be 75 opened and closed in normal use of the binder.

All of the parts comprising the herein-described binder locking mechanism may be made of a metallic material of light weight 80 and of small size and thus render the same easy to handle without sacrificing sturdiness of construction and durability in use. The parts are so associated and assembled that they may be readily replaced when worn by 85 new parts and thus economy in upkeep is accomplished. From the foregoing it will be apparent that I may produce a binder of the loose leaf type which is of inexpensive and of simple construction and very efficient and convenient in use and which may be quickly operated with a minimum effort.

Having thus described my invention in a specific embodiment, I am aware that numerous and extensive departures may be made 95 from the embodiment herein illustrated and described without departing from the spirit of my invention.

I claim:

1. In a loose leaf binder, the combination 100 of a pair of binder covers, a pair of binder posts carried by one of the covers, a binder-locking mechanism carried by the other cover and comprising a housing, said housing having pairs of aligned apertures therein, a rotatable rod disposed in said housing, a pair of relatively movable jaw members having threaded engagement with the rod toward and away from each other by rotation of the rod, said jaw members having 105 looped portions, said posts projecting through said aligned apertures and through the loops of said jaw members and adapted to secure the binder covers together, and a knob slidably mounted on said rod for rotating said rod.

2. In a loose leaf binder, the combination 120 of a pair of binder covers, a pair of binder posts carried by one of the covers, a binder-locking mechanism carried by the other cover and comprising a housing, said housing having a pair of aligned apertures 125 therein, a rotatable rod disposed in said housing, a pair of relatively movable jaw members having threaded engagement with the rod toward and away from each other by rotation of the rod, said jaw members having looped portions, said posts projecting through said aligned apertures and through the loop of said jaw members and adapted 130

to secure the binder covers together, and a knob slidably mounted on said rod for rotating said rod, a portion of said knob projecting through an aperture in the housing 5 and operable by the fingers of an operator to rotate said rod.

3. In a loose leaf binder, the combination of a pair of binder covers, a pair of binder posts carried by one of the covers, a binder locking mechanism carried by the other cover and comprising a housing, said housing having a pair of aligned apertures therein, a rotatable rod disposed in said housing, a pair of relatively movable jaw members having 15 threaded engagement with the rod toward and away from each other by rotation of the rod, said jaw members having looped portions, said posts projecting through said aligned apertures and through the loop of 20 said jaw members and adapted to secure the binder covers together, and a knob slidably mounted on said rod for rotating said rod, a portion of said knob projecting through an aperture in the housing and operable by 25 the fingers of an operator to rotate said rod,

and means for locking the knob against accidental rotation.

4. In a loose leaf binder, the combination of a pair of binder covers, a pair of binder posts carried by one of the covers, a binder locking mechanism carried by the other cover and comprising a housing, said housing having a pair of aligned apertures therein, a rotatable rod disposed in said housing, a pair of relatively movable jaw members having 30 threaded engagement with the rod toward and away from each other by rotation of the rod, said posts projecting through said aligned apertures and adjacent jaw members and adapted to secure the binder 35 covers together, and a knob slidably mounted on said rod for rotating said rod, a portion of said knob projecting through an aperture in the housing and operable by the fingers of an operator to rotate said rod, to 40 cause the jaw members to detachably grip the lateral surfaces of the posts.

In testimony whereof I hereunto affix my signature this 13th day of June, 1927.

NORMAN CLAYBAUGH DE LOSS.
